OTHER PUBLICATIONS

Design U.S. Appl. No. 29/708,155, filed Oct. 13, 2019 titled Latch.
(Continued)

Primary Examiner — Michael A. Pratt

(74) Attorney, Agent, or Firm — Dinsmore & Shohl LLP

(57) **CLAIM**

The ornamental design for a latch as shown and described.

DESCRIPTION

FIG. 1 is a front perspective view of a design of a latch; FIG. 2 is a front elevation view of the design of FIG. 1; FIG. 3 is a rear elevation view of the design of FIG. 1; FIG. 4 is a left side elevation view of the design of FIG. 1, with the right side elevation view being a mirror image of FIG. 4;

FIG. 5 is a top plan view of the design of FIG. 1; FIG. 6 is a bottom plan view of the design of FIG. 1; and, FIG. 7 is a front perspective view of a second embodiment of a latch design.

The broken lines shown in the drawings are included for the purpose of illustrating the unclaimed boundary and unclaimed portions of the latch.

1 Claim, 7 Drawing Sheets

See application file for complete search history.

- Design U.S. Appl. No. 29/605,186 entitled Refrigerating Apparatus filed May 24, 2017.
- European Design Patent Application No. 003847557-0001 entitled "Smart Cooler" filed Apr. 7, 2017.
- European Design Patent Application No. 003847557-0002 entitled "Smart Cooler" filed Apr. 7, 2017.
- European Design Patent Application No. 003847557-0003 entitled "Smart Cooler" filed Apr. 7, 2017.
- European Design Patent Application No. 003847557-0004 entitled "Smart Cooler" filed Apr. 7, 2017.
- European Design Patent Application No. 003847557-0005 entitled "Smart Cooler" filed Apr. 7, 2017.
- European Patent Office, International Search Report and Written Opinion for PCT/EP2017/080018 dated Jan. 25, 2018.
- International Preliminary Report on Patentability for PCT/EP2017/080018 dated May 28, 2019.

- Australian Patent Application No. 2017365438 filed May 6, 2019 entitled "Cooler".
- China Patent Application No. 201780072126.1 filed May 22, 2019 entitled "Cooler".
- European Design Patent Application No. 003476415-0001 entitled " " filed Nov. 22, 2016.
- European Design Patent Application No. 003476415-0002 entitled " " filed Nov. 22, 2016.
- European Design Patent Application No. 003476415-0003 entitled " " filed Nov. 22, 2016.
- European Design Patent Application No. 003476415-0004 entitled " " filed Nov. 22, 2016.
- European Design Patent Application No. 003476415-0005 entitled filed Nov. 22, 2016.
- European Design Patent Application No. 003476415-0006 entitled filed Nov. 22, 2016.
- European Design Patent Application No. 003476415-0007 entitled filed Nov. 22, 2016.
- Notice of Allowance received in Design U.S. Appl. No. 29/585,279 dated Apr. 22, 2020.
- Notice of Allowance received in Design U.S. Appl. No. 29/670,885 dated May 26, 2020.
- Notice of Allowance received in Design U.S. Appl. No. 29/670,888 dated May 26, 2020.
- Notice of Allowance received in Design U.S. Appl. No. 29/585,279 dated Jun. 24, 2020.
- Final Rejection Mailed in U.S. Appl. No. 15/819,950 on Jul. 16, 2020.
- Final Rejection Mailed in U.S. Appl. No. 16/264,057 on Jul. 20, 2020.
- Office Action received in China Patent Application No. 201780072126.1 dated Oct. 29, 2020.
- Rejection Decision Issued in China Patent Application No. 201780072126.1 mailed on Jun. 3, 2021.
- European Design Patent Application No. 003482694 entitled "Cooler" filed Nov. 25, 2016.
